UNITED STATES PATENT OFFICE.

VICTOR RITSCHARD, OF RIVERTON, NEW JERSEY, ASSIGNOR TO THE KEYSTONE WATCH CASE COMPANY, OF PHILADELPHIA, PENNSYLVANIA, A CORPORATION OF PENNSYLVANIA.

DESIGN FOR A WATCHCASE.

Application filed April 6, 1922. Serial No. 1,606. Term of patent 7 years.

To all whom it may concern:

Be it known that I, VICTOR RITSCHARD, a citizen of the United States, and a resident of Riverton, in the county of Burlington and State of New Jersey, have invented a new, original, and ornamental Design for Watchcases, of which the following is a specification.

In the accompanying drawing:

Figure 1 is a view in side elevation of a watch case embodying my new design; and Figure 2 is an edge view of the watch case.

I claim:

The ornamental design for a watch case, as shown.

VICTOR RITSCHARD.
